(57) **CLAIM**

The ornamental design for a child vest with ambidextrous arm sling, pockets and harness, as shown and described.

DESCRIPTION

FIG. 1 is a front perspective view of a child vest with ambidextrous arm sling, pockets and harness, showing my new design;

FIG. 2 is a front elevational view, thereof, with the harness removed for clarity;

FIG. 3 is a front left side perspective view, with the front right side being a mirror image thereof, harness removed for clarity; and,

FIG. 4 is a back elevational view thereof, with the harness removed for clarity.

It is understood that the broken lines within the claim design indicates stitching lines.
